UNITED STATES PATENT OFFICE.

JEAN B. OUELLETTE, OF NEW BEDFORD, MASSACHUSETTS.

LOOM ATTACHMENT.

1,347,399.

Specification of Letters Patent.

Patented July 20, 1920.

Application filed March 14, 1919. Serial No. 282,526.

To all whom it may concern:

Be it known that I, JEAN B. OUELLETTE, a citizen of the United States, residing at New Bedford, in the county of Bristol and 5 State of Massachusetts, have invented new and useful Improvements in Loom Attachments, of which the following is a specification.

My present invention pertains to looms, 10 and contemplates the provision of simple, inexpensive and easily applied means through the medium of which a weaver is enabled, with the expenditure of very little effort, to pull back or reverse the mechanism of the 15 loom to the point desired and as occasion demands.

With the foregoing in mind, the invention in all of its details will be fully understood from the following description and 20 claims, when the same are read in connection with the drawings, accompanying and forming part of this specification, in which:

Figure 1 is a side elevation of a loom equipped with my improvement.

Fig. 2 is a rear elevation of the same, showing the ordinary well known driving connections together with my improvement but with some parts omitted.

Fig. 3 is a detail side elevation showing 30 the circumferentially grooved gear of the improvement as the same appears when the equipment is actuated to hold said gear in engagement with the pulley on the top or crank shaft of the loom.

Fig. 4 is a detail view of the bracket employed in the application of the equipment.

Fig. 5 is an enlarged detail view of the circumferentially grooved gear, the said gear being shown as different in form from the 40 corresponding element shown in Fig. 2.

Fig. 6 is a rear elevation with parts omitted. Figs. 7 and 8 are views of the vertically swinging lever.

Fig. 9 is a detail view of the tappet on the 45 loom shaft 1.

Similar numerals of reference designate corresponding parts in all of the views of the drawings.

The loom is provided on the top or crank 50 shaft 1 with a pulley 2 fixed to said shaft and rotated incidental to the operation of the loom in the direction of the arrow shown

in Fig. 1. At 3 is a gear or pinion provided on the motor shaft 4 of the loom, and at 5 is a gear, intermeshed with the gear 3. This 55 gear 5 may be made of various diameters to bring about the reversing of the loom mechanism at a high or low rate of speed, as desired. The gear 5 is carried by a shaft 6, and on the shaft 6 is also arranged a pinion 7, which may be varied in diameter according to the speed of operation desired. Intermeshed with the pinion 7 is a gear 8 which constitutes an important element of my improvement. The said gear 8, I designate 65 a circumferentially grooved gear, inasmuch as it is provided with an offset portion 9 in which is a circumferential groove 10, adapted to receive and be engaged by the perimeter of the pulley 2.

The portion 9 of the gear 8 may be shaped 70 as shown in Fig. 2 or as shown in Fig. 5 without affecting my invention.

Mounted on the shaft 6 and fixedly attached to the loom frame 11 is the bracket 75 12 for the support of my novel equipment. The said bracket is provided with an upstanding arm 13.

Shaped into a hook 13^a at its lower end, Fig. 7 in order to engage and be supported 80 by the shaft 6, is a vertically swinging lever 15, provided at an intermediate point of its length with a trunnion 16 upon which the gear 8 is mounted and adapted to freely turn. The upper arm of the said lever 15 is 85 preferably, though not necessarily, provided with a series of lateral studs 17 for adjustment purposes.

Journaled in the arm 13 of the bracket 12 is a horizontal rock-shaft 18, to the opposite end portions of which upstanding arms 19 and 20 are fixed as shown in Figs. 2 and 6. The arm 19 is connected through a link 21 with the upper arm of the lever 15, and the arm 20 is connected to a handle rod 22, 95 which is preferably arranged as shown relatively to the loom in a bracket 22^a on the frame thereof and is equipped at its free end with a hand grasp 23. At its end remote from arm 13, the shaft 18 is disposed in a 100 socket bearing 18^a, fixed to the inner side of one side portion of the frame 11 as shown at the right of Fig. 6.

My invention also contemplates the use of

a bracket 24 Figs. 1 to 4 in addition to the bracket 12 and the socket bearing 13^e just referred to, said bracket 24 assisting in the support of the rock-shaft 18, and the said 5 brackets and socket bearing being the only elements that it is necessary to attach to the loom to hold my novel equipment in proper working position. The bracket 24 is fixed to one side of the bracket 12 and extends 10 downwardly therefrom and is fixed at its lower end to a portion of the loom frame as clearly shown in Fig. 1.

Heretofore, when a loom stopped it has been necessary for the weaver to pull the 15 loom mechanism back by hand, and this has been found to be a laborious operation.

The pulley 2 is fast on the crank shaft 1 of the loom and is only in motion when the loom is running. The gears 3, 5, 7 and 8 20 and the pulley 9 are constantly in motion, due to the fact that the gear 3 is fast on the motor shaft 4 which runs the loom. When the loom is running the attachment is positioned as shown in Fig. 1, the portion 9 of 25 gear 8 being then out of contact with the pulley 2. To pull back or reverse the mechanism of the loom, the weaver pulls on the handle 23 and thereby draws the gear portion or pulley 9 into engagement with the pulley 2 as shown in Fig. 3. Then when 30 the loom comes to the stopping point, a tappet 1^x adjustably fixed on the shaft 1 strikes the lever 15 and thereby moves the pulley 9 away from the pulley 2 and causes 35 the loom to stop. The tappet 1^x is adjustably fixed on the shaft 1, as stated, in order that it may be positioned to stop the loom where wanted.

It will be readily appreciated from the 40 foregoing that my novel attachment is simple and inexpensive in construction and is susceptible of being expeditiously and easily applied to a loom, without entailing the employment of highly skilled labor; and it 45 will also be appreciated that through the medium of the novel equipment the reversal or pulling back of the loom mechanism may be accomplished with the expenditure of extremely little effort on the part of the 50 weaver.

I have entered into a detailed description of the construction and relative arrangement of the parts embraced in the present and preferred embodiment of my invention, 55 in order to impart a full, clear and exact understanding of the said embodiment. I do not desire, however, to be understood as confining myself to the said specific construction and relative arrangement of parts, 60 since in the future practice of the invention various changes in the form and relative arrangement of the elements may be made, without involving departure from the scope of my invention as defined in my appended 65 claims.

Having described my invention, what I claim and desire to secure by Letters Patent, is:

1. The combination with the crank shaft of a loom, a tappet fast thereon, a pulley 70 also fast on said crank shaft, a motor shaft and a gear or pinion fast on the motor shaft; of a movable gear connected with the gear on the motor shaft and having a portion arranged to engage the pulley on the crank 75 shaft, and movable means carrying the said gear and manually operable to move the same into engagement with the pulley; said movable means being subject to movement in the opposite direction by the tappet on 80 the crank shaft to move the gear out of engagement with the pulley.

2. The combination with the crank shaft of a loom, a tappet fast thereon, a pulley also fast on said shaft, and a motor shaft 85 having a gear fast thereon; of a shaft having a gear fast thereon and intermeshed with the gear on the motor shaft, a lever pivotally mounted on the third-named shaft, a gear intermeshed with a pinion on the 90 third-named shaft and having a portion adapted to engage the pulley on the crank shaft, said gear carried by said lever, and manual means connected with said lever to move the said gear into engagement with the 95 pulley, said lever being subject to movement in the opposite direction by the tappet on the crank shaft.

3. The combination with the crank shaft of a loom, a tappet fast thereon, a pulley 100 also fast on the said shaft, a motor shaft, and a gear fast on said shaft; of a third shaft, a pinion and a gear fast on the third shaft, the gear being intermeshed with the gear on the motor shaft, a lever movable 105 about the third shaft as a center, a gear carried by said lever and intermeshed with the pinion of the third shaft and having a circumferentially grooved portion to receive and engage the periphery of the pulley on 110 the crank shaft, a rock shaft supported in the loom and having upstanding arms or cranks, a link connecting one arm or crank and the said lever on the third shaft and a handle rod connected to and extending from the other arm or crank, the lever on the third shaft being subject to movement in one direction by the tappet on the crank shaft.

4. A loom equipment comprising a bracket 120 having an upstanding arm, a lever having a shaft-receiving hook at one end, a circumferentially grooved gear mounted on and carried by the lever, brackets, a rock shaft journaled in the brackets and having cranks 125 or arms, a link connecting one crank and the lever, a handle rod connected to the other arm or crank of the rock shaft, and gearing also carried by the brackets and connected with the circumferentially grooved gear. 130

5. A loom equipment comprising a movable gear for establishing and interrupting connection between a pulley fast on the crank shaft of a loom and a gear fast on the 5 motor shaft of the loom, movable means carrying the first-named gear, a handle adapted to be arranged within convenient reach of a weaver or loom attendant, and a connection

between said handle and the movable means to move the movable means in one direction, 10 said movable means being subject to movement in the opposite direction by a tappet on the crank shaft of the loom.

In testimony whereof I affix my signature.

JEAN B. OUELLETTE.
